UNITED STATES PATENT OFFICE.

JAMES R. CLARK, OF LEXINGTON, KENTUCKY, ASSIGNOR TO CLARK GATE CO., OF LEXINGTON, KENTUCKY.

GATE.

1,297,099.

Specification of Letters Patent.

Patented Mar. 11, 1919.

Application filed January 27, 1919. Serial No. 273,340.

To all whom it may concern:

Be it known that I, JAMES R. CLARK, a citizen of the United States, residing at Lexington, in the county of Fayette and State 5 of Kentucky, have invented a new and useful Gate, of which the following is a specification.

This invention relates to gates and is more especially an improvement upon the structure shown in Patent #696,163, issued to me on March 25, 1902.

It has been the practice to ship the gate and its operating mechanism to the user in a knock down condition with suitable instructions whereby it might be set up without requiring the services of a skilled mechanic. The mechanism covered by the patent referred to could only be used upon a gate designed to swing open when moved 20 in one direction. If a gate was designed to be opened to the right but should be set up by the purchaser with the idea of having it open to the left, the parts could not be properly assembled so as to produce an operative structure and, as a result, some dissatisfaction and delays have resulted.

It is an object of the present invention to provide a gate operating mechanism which can be set up readily so as to open a gate 30 toward the right or to the left, the various parts of the operating mechanism being easily assembled and said mechanism working as efficiently when set up in either of the ways mentioned.

With the foregoing and other objects in view which will appear as the description proceeds, the invention consists of certain novel details of construction and combination of parts which will be hereinafter more 40 fully described and pointed out in the claims it being understood that various changes may be made in the construction and arrangement of the parts, without departing from the spirit, or sacrificing any of the 45 advantages of the invention as set forth in the appended claims.

In the accompanying drawings the preferred form of the invention has been shown.

In said drawings:

50 Figure 1 is a perspective view of the gate having the operating mechanism constituting the first invention.

Fig. 2 is a side elevation, on an enlarged scale, of the links of the operating mechanism.

Fig. 3 is a section on line 3—3, Fig. 2. Referring to the figures by characters of reference 1 designates a post to which a gate 2 is hingedly connected. Additional posts 3 are set up at opposite sides of the post 1 and at one side of the roadway, there being an operating lever 4 hingedly mounted between its ends on each post. These levers extend toward each other and terminate adjacent the upper end of the post 1 where they are provided with downwardly converging chains 5 secured at their lower ends to the upper end of a rod 6. The lower end of this rod has a stem 7 which is bent laterally as shown in Fig. 3 and terminates in a downwardly extending lug 8 constituting a retaining foot. A bearing block 9 is located between the post 1 and one of the posts 3 and hingedly connected thereto is a link 10 formed of side strips 11 secured together in any manner desired but providing a space therebetween. Fixedly secured between the side strips of the links 10 at a point between the ends thereof is a block 12 having a downwardly extending fork 13 each member of which has an opening 14 therein. The stem 7 is insertible into each one of these openings 14 and when so inserted the lug 8 will rest against the inner side of the fork as shown in Fig. 3, thus preventing withdrawal of the stem 7 from the fork unless the rod 6 should be moved downwardly to a substantially horizontal position.

Another link 15 is pivotally connected, 90 between its ends, to the free end of the link 10 and one end of this link 15 is pivotally connected, as at 16 to the gate 2 while its other end extends over the link 11 to form a weight 17.

It will be understood that when it is desired to have the gate swing to the right when opened, as indicated by the arrow in Fig. 1, the parts are to be assembled as shown in said figure whereas, should it be 100 desired to swing the gate to the left or oppositely to the movement indicated in Fig. 1, the parts of the apparatus can be reversed, the block 9 being placed at the opposite side of the post 1 and the rod 6 placed in engagement with the other member of the fork 13, while the link 15 would be attached to the other side of the gate. In either event a slight downward pull on the outer end of one of the levers 14 will cause the connected 110

ends of the links 10 and 15 to move upwardly, the weighted end 17 of link 15 passing over the pivoted or anchored end of the link 10 and then moving downwardly so 5 that the gate will thus be swung from one extreme position to the other, as disclosed in my patent hereinbefore mentioned. By providing the chain 5, a proper connection is always provided between the levers 4 and 10 the rod 6 whether the parts be set up for a right hand or a left hand gate. It will be noted that no fastening devices such as bolts or the like are necessary for connecting the rod 6 to the fork 13.

15 What is claimed is:

1. The combination with a swinging gate, of pivotally connected links, means for anchoring one of the links for swinging movement, a pivotal connection between the other 20 link and the gate, the last named link having an extension constituting a weight adapted to lap the anchored link, a fork connected to and depending from the anchored link, an operating lever, a rod connected to the operating lever, and a stem upon the rod and in- 25

sertible into either side of the fork when the rod is out of normal or upstanding position, there being a lug at the free end of the stem and constituting a retaining foot.

2. The combination with a swinging gate, 30 and pivotally connected links, one of said links being anchored to the ground and the other link being connected to the gate, of a fork extending downwardly from the anchored link, there being an aperture in each 35 member of the fork, operating levers, a rod, flexible connections between the rod and the operating levers, a laterally extending stem at the lower end of the rod, and a retaining foot or lug at the free end of the stem, said 40 lug and stem being insertible into one of the apertures when the rod is out of normal or upstanding position.

In testimony that I claim the foregoing 45 as my own, I have hereto affixed my signature in the presence of two witnesses.

JAMES R. CLARK.
